[57] CLAIM

The ornamental design for a base for a computer joystick, as shown and described.

DESCRIPTION

FIG. 1 is a rear isometric view of a base for a computer joystick showing our new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof;

FIG. 7 is a rear elevational view thereof; and,

FIG. 8 is a rear isometric view thereof.

The broken line drawing of a handle for the base for a computer joystick in FIG. 1 is for illustrative purposes only and forms no part of the claimed design.
